UNITED STATES PATENT OFFICE.

JOHN J. DONAHUE AND JOHN H. SULLIVAN, OF WORCESTER, MASSACHUSETTS.

DESIGN FOR A GAME-BOARD.

SPECIFICATION forming part of Design No. 25,349, dated April 7, 1896.

Application filed December 11, 1895. Serial No. 571,831. Term of patent 3½ years.

To all whom it may concern:

Be it known that we, JOHN J. DONAHUE and JOHN H. SULLIVAN, citizens of the United States, residing at Worcester, in the county of Worcester and State of Massachusetts, have invented or produced a new and useful Design for Game-Boards, of which the following is a full, clear, and exact description, which will enable others skilled in the art to make and use the same, reference being had to the accompanying drawing, forming a part of this specification.

Our invention or design relates to the boards which are employed in certain games which are played with movable pieces or checkers.

The nature of our design is fully represented in the accompanying drawing, to which reference is made.

As illustrated, our design for game-boards

comprises straight dark lines which appear 20 upon a light background, and which are arranged to outline a square figure having diagonal lines and central lines which are parallel with the sides of the figure.

Small circles or figures are arranged at the 25 intersection or crossing-points of the lines.

What we claim as new, and desire to secure by Letters Patent of the United States, is—

The design for a game-board, substantially as herein shown and described. 30

In testimony whereof we have hereunto set our hands in the presence of two subscribing witnesses.

JOHN J. DONAHUE.
JOHN H. SULLIVAN.
